ADJUSTABLE CHAIRS

Peter Stewart Fletcher, Delray Beach, Fla., assignor to
 Anton Lorenz, Ocean Ridge, Boynton Beach, Fla.
 Original application Feb. 9, 1956, Ser. No. 564,473, now
 Patent No. 2,958,371, dated Nov. 1, 1960. Divided
 and this application May 19, 1959, Ser. No. 814,254
 6 Claims. (Cl. 155—106)

This invention relates to reclining chairs and in particular to an improved seat control means which may be adjusted from a normal sitting position into a tilted position.

An object of the invention is to provide an improved seat control for reclining chairs in combination with any leg rest or leg-supporting platform which is normally disposed below the front of the seat but is automatically elevated into leg-supporting position when the chair is operated into a tilted position; which will have simple, dependable and effective mechanism for operating the seat with the leg rest or leg-supporting platform into and out of its effective leg-supporting position; which will employ novel and simple mechanism; and which will be relatively durable, compact and inexpensive.

Other objects and advantages will be apparent from the following description of several embodiments of the invention and the novel features will be particularly pointed out hereinafter in connection with the appended claims.

In the accompanying drawings:

FIG. 1 is a side elevation of a chair constructed in accordance with this invention, but with a side removed by a section just inside the chair in order to illustrate the mechanism employed for extending the leg rest, the parts being shown in the position occupied when the chair is in sitting position.

FIG. 2 is a similar view but with the parts in the tilted position; and

FIG. 2a is a schematic diagram illustrating the action of the linkage of FIGS. 1 and 2 used to extend the leg rest.

In the embodiment of the invention illustrated in FIGS. 1, 2 and 2a, the chair includes a support 1 having upright side members 2 that are spaced apart but connected by base members 3 and 4. A seat 5 and back rest 6 are disposed between the side members 2 of the support. The back rest is pivoted on a pivot or pin 7 adjacent its lower part, which pivot or pin 7 is carried by the support 1. The seat 5 is also pivoted at its rear end on the same pivot or pin 7. The seat 5, however, can be rocked on its pivot 7 independently of the back rest 6. A leg-supporting platform or rest 8 is disposed between the side members 2 of the support 1 below the forward edge of the seat 5 when the chair is in its normal sitting position, and this leg-supporting platform is mounted on a lazy tong device. This lazy tong device includes three pairs of links at each side of the seat which are carried by the support 1 and which in turn support the leg rest 8 and extend or retract it as desired.

These three pairs of links include one pair formed of links 9 and 10 which are hinged together by pivot or pin 11. The link 9 is pivotally connected by a pivot 12 to the support 1. The other link 10 is connected at its free end by pivot pin 13 to the leg rest 8. Another pair of links includes links 14 and 15 which are hinged together by a hinge 16. The free end of the link 14 is pivotally connected by a pin 17 to the support 1, and the link 15, at its free end, is pivotally connected by a pin 18 to one end of a link 19 of another pair of links. The other link 20 of this last pair is connected to the link 19 by a hinge 21, and the free end 20 is connected by the pivot pin 22 to the leg rest 8 below the pivot pin 13 by which the link 10 was connected to the leg rest. The link 14 is provided with

2

an extension 23 beyond its hinge 16 and this extension is pivotally connected by pin 24 to the link 10 intermediate of the ends of the latter. The link 19 of the third mentioned pair of links is pivotally connected intermediate of its ends by pivot pin 25 to the link 10 between the leg rest and the pivot pin 24.

It is to be observed that these three pairs of links at each side of the seat provide a lazy tong device for supporting the leg rest 8 from the support 1, and the links are so interconnected that we have a plurality of successive quadrilaterals of links arranged in succession or tandem with the leg rest 8 forming part of one quadrilateral of links, and with the support 1 forming with the links of an end pair of links a third quadrilateral that is arranged in tandem with the other two quadrilaterals. Thus, if any one of the links of any quadrilateral of links is operated back and forth, the lazy tong device formed of the succession of three quadrilateral linkages will cause the leg to be extended upwardly and forwardly into the supporting position shown in FIG. 2 or retracted beneath the forward edge of the seat 5.

To operate this lazy tong device a connecting link 26 is pivotally connected by a pin 27 to one of the links, such as the links 9, the other end of the connecting link 25 26 being pivotally connected by a pin 28 to an arm 29 which depends from the back rest 6 below the pivot pin 7 on which the back rest may tilt. Thus, when the back rest 6 is moved rearwardly at its upper end, its lower end will move the link 26 endwise to the left in FIGS. 1 and 2, and thus rock the link 9 to the left in FIGS. 1, 2 and 2a and cause an extension of the lazy tong that elevates the leg rest 8 to a position in front of the seat 5, as shown in FIG. 2. In order to support the forward edge of the seat 5 and also elevate that forward edge when the back rest 6 is moved into a tilted position, the seat 5 is provided with a descending lug 30 at each side of the seat, and each lug 30 at its lower end mounts a roller 31 on a rolling pivot 32, and this roller 31 rolls on the adjacent connecting link 26.

The link 26 therefore serves to support the seat 5 because the lug 30 is disposed forwardly of the pivot 7 on which the seat is mounted to rock or tilt. Then, when the back rest 6 is moved into a tilted position, it automatically causes an extension of the lazy tong device and an elevation of the leg rest 8 into a position approximately at the level and in front of the forward edge of the seat 5, and because the link 26 rises during this movement, that link will act through the roller 31 and lug 30 to elevate the forward edge of the seat 5, as shown in FIG. 2. When the back rest 6 is returned to its upright or sitting position, shown in FIG. 1, it will pull endwise on the link 26 and retract the leg rest to its sitting position, shown in FIG. 1, and lower the front edge of the seat 5.

It will be noted that the roller 31 is supported, raised and lowered by a four bar linkage. This four bar linkage at each side of the seat is formed of the extension 29 of the back rest, the connecting link 26, and the link 9 below the pivot 12 to the pivotal connection 27 of the link 26. The frame of the chair which supports the pivots 7 and 12 is the fourth link of the four bar linkage. The roller 31 rides on and is operated by one of the links 26 of this four bar linkage, and hence the latter plus the roller 31 and the lug 30 control the angle of inclination of the seat 5.

It will be understood that there is one of these lazy tong arrangements at each side of the support so as to support the leg rest at each side thereof, and suitable stops, not shown, may be employed to limit the tilting movements of the seat and back rest. Each lazy tong arrangement in this example of the invention has its links comprising it operatively connected by means which includes at least one extension of one of the links of each

arrangement. In the drawings of this example, the links 9 and 10 may be considered to be the first pair of links, links 14 and 15 may be considered the second pair of links, and links 19 and 20 may be the third pair of links. The extension of one of the links is the extension 23 of the link 14 of the second pair of links. In this example one of the links of the first pair is always pivoted to the support, and the other of link of that pair is always pivoted to the leg rest, also one of the links of the second pair is always pivoted to the support or frame, and the other link of that pair is always pivoted to one link of the third pair. The other link of the third pair is always pivoted to the leg rest. The extension of at least one of the links of a pair is pivoted to a link of another pair.

It will be understood that various changes in the details and arrangements of parts which have been herein described and illustrated in order to explain the nature of the invention may be made by those skilled in the art within the principle and scope of the invention as expressed in the appended claims.

This application is a division of my copending application Serial Number 564,473, filed February 9, 1956, now Patent No. 2,958,371, issued November 1, 1960.

I claim:

1. An adjustable chair comprising a support, a back rest and a seat, said back rest and said seat being pivotally mounted for limited rotation on axes at the rear of said seat and the lower part of said back rest, said back rest having an extension depending below its axis of rotation, a supporting link pivoted to said support and generally about upright when the back rest is upright, an actuating link articulately connecting said depending extension to said supporting link so that said extension, said links and said support together form a quadrilateral linkage, and a free roller carried by said seat forwardly of the axis of rotation of the seat rolling on said actuating link, and supporting said seat forwardly of its axis by which it is pivotally mounted, whereby when said back rest is rotated rearwardly on its said axis it will actuate said quadrilateral linkage and through said roller will raise the forward part of said seat.

2. An adjustable chair comprising a support, a back rest and a seat pivoted to said support and movable between sitting and tilted positions, an actuating link at each side of the seat connected to said back rest below its said pivot and extending forwardly therefrom, a generally upright supporting link which is pivoted to said support and to the forward end of said supporting link, and a free roller carried by each side portion of the seat and each rolling on and supported by the said actuating link at that side of the seat for supporting the forward part of the seat and raising it when the back rest is tilted rearwardly and said actuating link is moved forwardly.

3. An adjustable chair comprising a frame, a back rest and a seat pivotally mounted on said frame for limited rocking by the back rest about an axis near its lower

edge and by the seat about an axis near its rear edge, said back rest rising from adjacent the rear edge of the seat and having a portion depending well below its pivotal mounting in a position to rise and move forwardly 5 when the back rest is tilted rearwardly, one link pivoted to said support forwardly of the back rest, an actuating link having its rear end connected to said depending portion of the back rest, at well below the pivotal mounting of the back rest, extending forwardly therefrom and having its front end connected to a part of said one link which has an upward component of movement during the period while the back rest is being tilted rearwardly and the actuating link is moved thereby, and means by which said seat forwardly of its pivoted rear edge, is supported 10 by and has relative movement along said actuating link as the latter actuates said one link, whereby when said back rest is tilted rearwardly it causes forward and upward movement of said actuating link and in so moving it raises said roller carried by said seat and rocks 15 said seat upwardly about its pivoted mounting at its rear edge.

4. The chair according to claim 3, wherein said means supporting said seat includes a free roller carried by the seat and rolling on said actuating link.

5. An adjustable chair comprising a frame, a generally upright back rest pivoted near its lower edge to said frame and having a part depending downwardly therefrom and moving forwardly and upwardly in an arc when said back rest is tilted rearwardly, a seat pivoted near its rear edge 20 to said frame, one link connected at one end to said support and having a part that rises at some time during its movement from a vertical position, and actuating link connected at its rear end to the depending part of said back rest, at a point well below the pivotal mounting of the back rest, and at its forward end to said one link to cause it to swing when the back rest is tilted rearwardly, and means carried by said seat well forwardly of its rear edge and supported by and being freely movable along 25 said actuating link for supporting the forward part of said seat and raising it as the actuating link is raised and moved forwardly when the back rest is tilted rearwardly.

6. The chair according to claim 5, wherein said means carried by said seat includes a free roller which rolls on said actuating link as the latter is moved endwise.
